UNITED STATES PATENT OFFICE.

WILLIAM PATRICK DAY, OF CLEVELAND, OHIO.

RAILWAY-TIE.

1,175,244.

Specification of Letters Patent.

Patented Mar. 14, 1916.

Application filed July 8, 1915. Serial No. 38,729.

To all whom it may concern:

Be it known that I, WILLIAM P. DAY, a citizen of the United States, residing at Cleveland, in the county of Cuyahoga and State of Ohio, have invented certain new and useful Improvements in Railway-Ties, of which the following is a specification.

This invention comprehends certain new and useful improvements in railway ties, 10 and particularly to that type of tie or rail support embodying spaced members extending transversely of the rails and rail supporting plates or chairs extending longitudinally beneath the rails and riveted or 15 otherwise operatively secured to the transversely extending members.

The general object of my present invention is to provide a rail supporting structure of the character described that may be 20 very cheaply made, that will be strong and rigid, and that will be adaptable for use in either open or closed track work and in ballast or concrete, as desired.

A further object is to so construct the 25 chair plates that they will be particularly well reinforced and strengthened by forming thereon longitudinally extending lateral and downwardly extending flanges of a peculiar shape, which flanges perform the 30 triple function of strengthening the plate, acting to retain the ballast or gravel beneath the plate and preventing lateral movement of the plates and the supporting structure as a whole. Furthermore, the peculiar 35 shape given to these flanges and their relation to the plate is such that the flanges tend to prevent longitudinal movement of the plates.

Another object is to so form the members 40 that connect the pair of plates to each other that biting edges will be provided extending transversely of the line of the rails which will grip down into the sub-soil or ballast and prevent the tie structure as a whole 45 from creeping forward, that is, longitudinally of the rails.

A further object is to so construct the supporting or chair plates and the flanges thereon that ballast may be tamped beneath these 50 chair plates but will be retained after being so tamped.

With these and other objects in view as 55 will more fully appear as the description proceeds, the invention consists essentially in the particular construction, arrangement

and combination of the parts as is herein-after more fully described and claimed.

For a full understanding of the invention and the merits thereof reference is had to the following description and accompanying 60 drawing, in which—

Figure 1 is a perspective view of my improved rail support. Fig. 2 is a top plan view of one of the chair plates after being formed. Fig. 3 is a side elevation of the chair plate 65 shown in Fig. 2. Figs. 4 to 7 are sections taken respectively on the lines 4—4, 5—5, 6—6 and 7—7 of Fig. 2.

Referring to these drawings it will be seen that my improved tie comprises a pair 70 of angle irons 2 which are disposed in spaced relation to each other and are intended to extend transversely of the track rails. These transversely extending angle irons 2 are arranged with their horizontal 75 flanges extending away from each other, as shown in Fig. 3, and at their ends these angle irons 2 are riveted, bolted, or otherwise connected to a pair of chair plates 3 which extend lengthwise of the track and 80 are intended to extend each beneath one of the rails of the track. These chair plates 3 have a peculiar form which is the result of a long course of experiments and tests, and this peculiar form is such as to give a maximum strength to the chair plate at a minimum cost in addition to giving certain other 85 advantages previously referred to.

Each plate 3 is of steel and may be from $\frac{5}{16}$ to $\frac{1}{4}$ an inch thick. Each plate has downwardly and outwardly extending lateral flanges 4. The horizontal portion of the plate is gradually narrowed from its ends toward its middle or waist, and as a consequence the flanges 4 gradually narrow from 95 the middle toward the ends and when the flanges 4 are formed, as by stamping or pressing the sheet metal of the plate, the lower edges 5 of these flanges as illustrated in Fig. 2 will curve slightly downward and outward. The flanges are disposed along their entire extent at the same angle, which angle is preferably about 45° , as illustrated by the sectional views, Figs. 4 to 7. The flanges 4 terminate short of the ends or extremities of the plate 3 to provide a transverse flat terminal portion at each end of the plate, designated 6, to permit the transverse members 2 to extend across the extremities of the plate and be attached thereto by 100 105 110

rivets or bolts 7. The plate is formed with openings 8 to receive rail engaging clamps (not shown) of any ordinary type usually used in connection with metallic or concrete 5 chairs or ties. The particular means for attaching the rails to this particular rail support and tie form no part of the present invention.

Attention is now directed to the advantages accruing from the construction described. Inasmuch as the members 2 are so placed that their vertical flanges extend downward, these vertical flanges will bite into the ballast or sub-soil of the road bed, 10 and prevent any longitudinal movement of the tie structure. By gradually narrowing the plate 3 toward its middle from each end and forming the inwardly bowed downwardly and outwardly extending flanges 4 I 15 secure a maximum strengthening of the plate, a much greater strengthening than would occur if the plate had straight parallel sides with the flanges 4 extending down and out from these parallel sides and having 20 a uniform width along their entire extent. The stamping or pressing of the plate 3 with the flanges 4 acts to warp the plate, not in the sense that it at all affects the flatness of the body of the plate, but only as regards 25 the sides 4. It is the bowing inward of these flanges that gives the requisite stiffness to the plate and prevents the plate from buckling or becoming otherwise deformed under 30 service conditions. These flanges 4, furthermore, bite into the ballast or sub-soil of the road bed and prevent transverse sluing of the tie and track thereon, and furthermore these flanges will retain the ballast or gravel 35 that is tamped under the plate 3. It will 40 be noted in Fig. 3 that when the tie is in place the lower edges of the flanges 4 extend downward in a curve, this curve gradually rising at each end toward the members 2. This permits ballast to be readily 45 tamped beneath the plate 3 and yet be held in place thereon when tamped.

This form of track supporting structure has been tried in practice and under service

conditions and has been found to possess great strength with a minimum of weight. 50

It is a tie particularly adapted for use in open or closed track work with ballast or embedded in concrete.

What is claimed is:

1. A rail supporting structure comprising 55 a pair of transversely extending spaced connecting bars and rail supporting plates rigidly mounted upon said connecting bars and extending transversely thereto and parallel to the rails of a track, each of said plates 60 comprising a rail supporting plate having a terminal portion of a maximum width resting upon the said connecting bars, the plate immediately inward of said terminal portion being gradually narrowed in width toward 65 the middle of the plate, said plate being flat for its entire length and the sides of the plate being formed with outwardly and downwardly extending flanges and the lower edge of each flange being downwardly 70 curved from its ends toward its middle, said flanges extending from one terminal portion of the plate to the other terminal portion thereof and the lower edges of the flanges being substantially parallel to each other 75 and to the longitudinal axis of the plate.

2. A rail supporting structure comprising 80 transversely extending spaced connecting angle irons having downwardly extending flanges, and a pair of rail supporting plates mounted upon said angle irons, said plates extending parallel to each other and transversely to the angle irons and each plate being gradually contracted in width 85 toward its middle, said contracted portion of each plate being provided with oppositely disposed downwardly and outwardly extending flanges.

In testimony whereof I affix my signature in the presence of witnesses.

WILLIAM PATRICK DAY.
